UNITED STATES PATENT OFFICE.

JACOB MITZ, OF SPRINGHILL, NOVA SCOTIA, CANADA.

DESIGN FOR AN INKWELL.

60,498.

Specification for Design.

Patented Feb. 28, 1922.

Application filed September 26, 1921. Serial No. 503,406. Term of patent 7 years.

To all whom it may concern:

Be it known that I, JACOB MITZ, a citizen of Ukraine, residing at Springhill, in the Province of Nova Scotia and Dominion of Canada, have invented a new, original, and ornamental Design for an Inkwell, of which the following is a specification, reference being had to the accompanying drawing, forming part thereof.

The figure is a view in perspective of an inkwell, showing my new design.

I claim:

The ornamental design for an inkwell, as shown.

JACOB MITZ.
